UNITED STATES PATENT OFFICE.

LEWIS L. ROGERS, OF ORANGE, MASSACHUSETTS.

PRINTER'S QUOIN.

SPECIFICATION forming part of Letters Patent No. 794,188, dated July 11, 1905.

Application filed March 22, 1905. Serial No. 251,386.

To all whom it may concern:

Be it known that I, LEWIS L. ROGERS, a citizen of the United States, and a resident of Orange, in the county of Franklin and State 5 of Massachusetts, have invented certain new and useful Improvements in Printers' Quoins, of which the following is a specification.

My invention has relation to new and useful improvements in printers' quoins of that 10 character or type which embody in their construction wedge-shaped sections or parts arranged in contact with each other on their inclined faces and having their opposite faces parallel and adapted to engage, respectively, 15 with the type-form and the chase, said sections being longitudinally movable upon each other to increase the distance between said opposite faces, so as to exert a clamping or wedging action to maintain the type-form im- 20 movably in position within the chase.

The primary object of the invention is to provide a quoin of the general character mentioned with improved and simplified locking means to prevent the sections from becoming 25 accidentally loosened and dislodged from wedging position after they have been adjusted to lock the form in the chase.

I would state that I am aware that the prior art discloses pivotally-supported and spring- 30 actuated pawls, detents, similarly-actuated cam-locking devices, and also slidingly-dis- posed latches carried by one of the quoin-sections adapted to engage a serrated or notched 35 surface on the opposite section of the quoin; and it is therefore a further object of my in- 40 vention to simplify the existing art by dispensing with all auxiliary means for effecting the engagement of the locking-piece with the serrated surface and also to provide an im- 45 proved bearing or housing for the locking- piece which will obviate the use of pivot-pins, shafts, and similar mountings.

The invention consists in the peculiar construction and arrangement of parts, to be 45 more fully described hereinafter, and the novelty of which will be particularly pointed out and distinctly claimed.

I have fully and clearly illustrated my in-

vention in the accompanying drawings, to be taken as a part of this specification, and 50 wherein—

Figure 1 is a plan view of a portion of a chase and of a portion of a piece of furniture with the improved quoin arranged in operative position, the heel of one of the sections of the 55 quoin being broken away to show the locking-piece in operative position to prevent backward movement of the sections. Fig. 2 is a longitudinal central section through the improved quoin. Fig. 3 is a detail perspective 60 view of the locking-piece. Fig. 4 is a sectional view on the line 4-4 of Fig. 2.

Proceeding with a description of the invention as shown in the drawings, A designates one of the wedge-shaped sections or halves of 65 the quoin, and B the other section, shown as being duplicates in form and construction and with the exception of the improvements to be hereinafter described of a well-known type, each section being formed on its oppo- 70 site sides with longitudinal rack-sections 1, 2, the said racks on the respective sections being adapted to be engaged by a suitable pinion-key (not shown) for moving the quoin-sections relatively to each other in opposite 75 directions to increase or decrease the width of the quoin accordingly as it is desired to wedge the form in the chase or to release the same therefrom.

Each of the quoin-sections above referred 80 to is provided on its inclined face with a central longitudinal rib 3, in which is formed a series of transverse rack-teeth 4, the series be- 85 ginning at approximately the toe of the sec- tion and terminating at a point about half-way of the length of the rib, the remaining por- 90 tion of which from the end of the series being left smooth and slightly higher than the points of the rack-teeth for a purpose to be set forth hereinafter.

In the heel 5 of each wedge-shaped section is formed a slot or chamber 6, opening through both the inclined face and the end of the sec- 95 tion, and in the floor or bottom of this slot is formed a circular seat or depression 7, the curved wall 8 of which at the end toward the

heel of the section merges with the bottom of the slot 6 in such a manner as to provide a lug or projection 9, substantially as shown in the drawings, said lug performing a function to be more fully set forth presently.

The chamber or slot 6 is adapted to receive a loosely-disposed locking-piece 10, which consists of a block of suitable metal formed at one end to provide a circular head or disk 11 and at its opposite end formed with a flaring locking part 12, having oppositely-disposed engaging points or teeth 15, said disk and locking part being connected by a reduced or neck portion 13. When this locking-piece is arranged in operative position on one of the quoin-sections, the disk or head 11 is placed in the circular seat 7, with the locking or engaging part 12 projecting through the open end of the slot 6 and beyond the heel end of the quoin-section, the said circular seat and similarly-formed head 11 providing for a swinging or pivotal movement of the locking-piece.

The smooth portions of the medial ribs 3 at the parts extending from the serrated or rack portions being slightly higher than the points of the teeth of the latter, as heretofore stated, it will be seen that when the sections are disposed in operative relation they will ride readily and easily on the said smooth parts of the ribs and that when the quoin-sections are laid together the rib on each section extends into the slot 6 in the heel of the opposite section, so that the rib on one section forms with the lug 9 in the slot 6 of the other section a contracted space 14, in which the neck 13 of the locking-piece is loosely lodged. The lug 9 is so located that the space 14 between it and the rib on the opposite section is of less width than the diameter of the disk 11, the arrangement being such that the opening through which the disk may be removed is sufficiently reduced to prevent dislodgment of the disk from the seat 7, whereby the locking-piece is securely held against removal while the inclined faces of the quoin-sections are maintained in contact. By this construction and arrangement of parts the locking-piece is readily movable into and out of position in the seat of either of the quoin-sections when the latter are separated, but is securely held in pivotal relation thereto whenever said sections are disposed in operative relation to each other.

It will be seen that the flaring or dovetail shape of the locking-piece presents a locking edge or point for engagement with the rack on the ribs 3 no matter in which of the sections it may be placed and irrespective of which edge or point is presented to the rack. The locking-piece, it is apparent, may be used with equal convenience in the slot provided for its reception in either of the sections.

To utilize my improved quoin, the disk portion 11 of the locking-piece is placed in the heel-slot 6, and then the sections of the quoin

are laid together, with their inclined faces in contact and the quoin placed in position as usual between the frame of the châse and the piece of furniture, and the sections are then moved longitudinally to wedge the form in place. When the proper tightness has been attained, the locking-piece is turned to bring one of the points 15 into engagement with the rack on the rib 3 of the opposite section, and the sections are thereby held securely against displacement, it being obvious that the tendency of the sections is to jar back on their inclines, so that the engagement of the point of the locking-piece with the rack is tightly held and maintained.

What I claim is—

1. A printer's quoin, comprising wedge-shaped sections adapted to engage each other on their inclined faces, a locking-piece removably disposed on one of the sections and being adapted to engage the opposite section to lock the sections against backward movement, and means whereby said locking-piece is held against removal while the sections are in operative relation and can be removed only when the sections are separated.

2. A printer's quoin, comprising wedge-shaped sections adapted to engage each other on their inclined faces, a seat in one of said sections, a locking-piece removably and pivotally disposed in said seat and adapted to engage the opposite section to lock the sections against backward movement, and means whereby said locking-piece is held against removal while the sections are in operative relation and can be removed only when the parts are separated.

3. A printer's quoin, comprising wedge-shaped sections adapted to engage each other on their inclined faces, a circular seat in one of said sections, a locking-piece having a circular head removably and pivotally disposed in said seat and also having means to engage the opposite section to lock the sections against backward movement, and means whereby said locking-piece is held against removal while the sections are in operative relation and can be removed only when the sections are separated.

4. A printer's quoin, comprising wedge-shaped sections adapted to engage each other on their inclined faces, a slot in one of said sections having a circular seat in its bottom portion, a locking-piece movable in said slot and provided with a head pivotally and removably disposed in said seat, said locking-piece being provided with means to engage the opposite section to lock the sections against backward movement, and means whereby said locking-piece is held against removal while the sections are in operative relation and can be removed only when the sections are separated.

5. A printer's quoin, comprising wedge-shaped sections adapted to engage each other

on their inclined faces, one of said sections being formed with a rack and the opposite section having a slot in its heel portion and a circular seat in the wall of said slot, a locking-piece movable in said slot and provided with a head pivotally and removably disposed in said seat, said locking-piece being also provided with a tooth or point to engage the rack on the opposite section to lock the sections against backward movement, and means whereby said locking-piece is held against removal while the sections are in operative relation and can be removed only when the sections are separated.

6. A printer's quoin, comprising wedge-shaped sections adapted to engage each other on their inclined faces, one of said sections being formed with a rack and the opposite section being provided with a slot in its heel portion having a circular seat in its bottom wall and a projection at one end of said seat, a locking-piece movable in said slot and provided with a head pivotally and removably disposed in said seat, said locking-piece being also provided with a tooth or point to engage the rack on the opposite section to lock the sections from backward movement, and means coacting with said projection to maintain the head of the locking-piece in its seat and against re-

moval while the quoin-sections are in operative relation. 30

7. A printer's quoin, comprising wedge-shaped sections adapted to engage each other on their inclined faces, one of said sections being formed with a rack, and the opposite section being provided with a slot in its heel portion having a circular seat in its bottom wall and a projection at one end of said seat, a locking-piece movable in said slot and being provided with a head pivotally and removably disposed in said seat and being also provided with an engaging part to engage the rack on the opposite section, the said head and engaging part of the locking-piece being connected by a neck portion which lodges on 45 said projection in the slot of the quoin-section, and means carried by the opposite quoin-section coacting with said projection to prevent removal of the head from its seat when the sections are in operative relation. 50

Signed at Orange, in the county of Franklin and State of Massachusetts, this 20th day of March, A. D. 1905.
